UNITED STATES PATENT OFFICE

165,459

MANICURE KIT

Stuart S. Joslyn, Chester, Conn., assignor to C. J. Bates & Son, Chester, Conn., a firm

Application October 31, 1950, Serial No. 12,786

Term of patent 7 years

(Cl. D87—3)

To all whom it may concern:

Be it known that I, Stuart S. Joslyn, a citizen of the United States, residing at Chester, in the county of Middlesex and State of Connecticut, have invented a new, original, and ornamental design for a Manicure Kit, of which the following is a specification, reference being had to the accompanying drawings, forming part hereof:

Fig. 1 is a perspective view of a manicure kit in the closed position;

Fig. 2 is a perspective view of a manicure kit in the open position.

The back of the kit is substantially plain.

My design for a manicure kit is characterized by the flat isosceles-shaped frame ends associated with the tubular element connecting the

tops of said frame ends and the chain handle extending across the top of the frame, all as shown.

I claim:

The ornamental design for a manicure kit, as shown and described.

STUART S. JOSLYN.
